UNITED STATES PATENT OFFICE.

FRANK J. HERRICK, OF NEW BRITAIN, CONNECTICUT, ASSIGNOR TO THE
NORTH & JUDD MANUFACTURING COMPANY, OF SAME PLACE.

DESIGN FOR A HEEL-PROTECTOR.

SPECIFICATION forming part of Design No. 21,889, dated October 11, 1892.

Application filed August 11, 1892. Serial No. 442,815. Term of patent 7 years.

To all whom it may concern:

Be it known that I, FRANK J. HERRICK, a citizen of the United States, residing at New Britain, in the county of Hartford and State of Connecticut, have invented and produced a new and original design for Heel-Protectors, of which the following is a specification, reference being had to the accompanying drawings, forming part thereof.

10 Figure 1 is a perspective view of a heel-protector, showing my design. Fig. 2 is a like view of the same as viewed from a different direction.

15 *a a* designate two flat plate-like wings standing substantially parallel to each other

and connected together by a substantially semicylindrical portion *b*, as shown, whereby the same presents a U-shaped form in end view somewhat resembling the form of a horseshoe. The thickness of my heel-protector in edge view is uniform, so that when thus viewed the side faces extend around the U figure substantially parallel to each other.

20 What I claim is—

25 The design for a heel-protector, as herein shown and described.

FRANK J. HERRICK.
